SURFACE DENSITY GAUGE

William F. Troxler, Raleigh, N.C., and David B. Auld,
Redwood Estates, Calif., assignors to Troxler Elec-
tronic Laboratories, Inc., Raleigh, N.C., a corporation
of North Carolina

Filed Jan. 11, 1966, Ser. No. 1,498

Term of patent 14 years

(Cl. D52—6)

FIG. 4

FIG. 1

FIG. 5

FIG. 2

FIG. 3

FIGURE 1 is a top plan view of a surface density gauge embodying our new design.

FIGURE 2 is a side elevational view taken in the direction of arrow 2 shown in FIGURE 1.

FIGURE 3 is a side elevational view taken in the direction of arrow 3 shown in FIGURE 1.

FIGURE 4 is a side elevational view taken in the direction of arrow 4 shown in FIGURE 1.

FIGURE 5 is a bottom view.

The undisclosed side of the surface density gauge is a mirror image of the opposite side thereof.

We claim:

The ornamental design for a surface density gauge, substantially as shown and described.
